UNITED STATES PATENT OFFICE.

BERTIE S. HARRINGTON, OF FORT WORTH, TEXAS.

BLENDING MACHINE.

Application filed July 15, 1925. Serial No. 43,693.

The present invention has to do with the preparation of substances such as lard, lard compounds, and the like, and is particularly concerned with a machine for improving the texture of such substances by the application thereto of a blending action.

The principal object of the invention is to provide a continuously operable blending machine of novel construction, arrangement and operation, which is capable of smoothing out all lumps in the substance being treated, eliminating any unevenness, in consistency, and whipping the air content uniformly throughout the mass, whereby to give a more desirable cream-like texture to the substance.

Other objects and advantages not specifically referred to in this disclosure will be evident to those skilled in the art upon a full understanding of the construction, arrangement and operation of the machine.

For the purpose of exemplification, one embodiment of the invention is set forth in the accompanying drawings and in the following detailed description, but as other variously modified embodiments are also obviously within the purview of the invention, the form herein presented is not to be considered as limiting the spirit of the invention short of its intended scope as defined in the appended claims.

In the drawings—

Fig. 1 is a sectional view of the machine, taken longitudinally of the same;

Fig. 2 is another sectional view, taken transversely on the line 2—2 of Fig. 1;

Fig. 3 is an enlarged view, showing the stator partly in side elevation and partly in section and showing the rotor in side elevation; and

Fig. 4 is an end view of the stator and the rotor.

The machine illustrated in the drawings is characterized by a casing 10 which is mounted on a base 11 or other suitable support. The casing provides a cylindrical chamber in which a stator 12 and rotor 13 are positioned. The substance to be treated in the machine enters the casing through an inlet port 14 in one end wall of the

chamber, and, after being thoroughly treated therein between the stator and the rotor, leaves the casing through two outlet ports 15 which communicate with an inwardly opening annular groove 16 in the side wall of the chamber.

The stator 12 is a hollow cylindrical member which is so positioned within the casing as to constitute a lining for the side wall of the chamber. The portion of the stator which spans the groove 16 in the side wall is provided with a large number of fine radial perforations 17 through which the substance being treated must pass before leaving the casing through the groove 16 and the outlet ports 15.

The rotor 13 is a member which has a cylindrical medial portion 18, two conical end portions 19 and a hub portion 20. The rotor is positioned concentrically in the stator, with the cylindrical portion 18 of the rotor in closely fitting association with the perforated portion of the stator, and is rotated at a high rate of speed by a drive shaft 21 to one end of which the hub portion 20 is secured. The shaft 21 is journaled at one side of the hub portion in a roller bearing 22 supported by the casing, and passes through a packed gland 23 in one end wall. The hub portion 20 is provided with a number of longitudinally extending ducts 24 which permit the substance entering the casing through the inlet port 15 to flow in two substantially equal streams about both ends of the rotor and into the two tapering spaces between the conical end portions of the rotor and the opposed cylindrical portions of the stator.

The outer surface of the rotor 13 is provided with a plurality of longitudinally extending grooves or feedways 25 which are disposed at regular intervals circumferentially of the same. The feedways 25 and the resulting ribs 26 therebetween are preferably about equal in width. The outer surface of the rotor is also provided with a plurality of helically extending grooves or feedways 27, but the feedways 27 are restricted to the conical end portions and terminate at the margins of the cylindrical

portion. The feedways 27 in one end portion simulate right hand threads, while those in the other end portion simulate left hand threads. The feedways 27 are of 5 about the same proportioning and spacing as the feedways 25, and the intersections between the feedways form a large number of small rectangular fingers 28. The bottoms of all of the feedways in the rotor are 10 preferably equidistant from the axis of rotation and the depth of the grooves in the conical end portions of the rotor is accordingly less than in the cylindrical medial portion.

15 The machine operates as follows:

The rotor in the machine is rotated at a high rate of speed—preferably from 1200 to 1500 R. P. M. The substance to be treated is fed under pressure into the machine through the inlet port 14, after first 20 being filtered through a preliminary strainer such as that illustrated in dotted lines at 29. It is not essential that a strainer be employed in connection with the machine, 25 but it is desirable for the reason that the substance to be treated frequently contains foreign bodies such as wood chips, nail heads, tacks and the like, which might injure the machine were they permitted to enter the 30 same.

After the substance enters the machine, it divides into two streams, one stream flowing outwardly about that end of the rotor which is nearest to the inlet port, and the other 35 stream flowing first through the ducts 24 in the hub portion of the rotor and then outwardly about the other end of the same.

The two streams then enter the tapering 40 spaces between the conical end portions of the rotor and the opposed cylindrical portions of the stator, and move toward each other through and about both the longitudinally extending feedways 25 and the helically extending feedways 27. The substance 45 takes on the speed of the rotor as it enters the feedways and is given a rolling movement therein. The substance traveling toward the cylindrical portion of the rotor in the feedways 25 commingles at the corners 50 of the fingers 28 with the substance moving in the feedways 27, and the substance outside of the feedways in the tapering spaces between the stator and the rotor is worked by the fingers 28. After the substance has 55 thus been thoroughly mixed and worked, it enters the feedways 25 in the cylindrical portion of the rotor and is expressed from the feedways through the perforations in the stator. Each of the feedways 27 is in 60 communication with each of the perforations 17 for such an infinitesimally small amount of time that the substance is highly comminuted by the shearing action of the ribs 26 in passing the perforations 17 during 65 the egress of the substance.

When the substance leaves the outlet ports 15 of the machine, all of the lumps and unevennesses in the texture of the same will have been eliminated, leaving the substance in a perfectly homogeneous condition, with a lighter color, due to the thorough beating and distribution of the air content, and with a greater specific gravity in relation to the color. 70

I claim:

1. A blending machine, comprising two closely fitting members mounted for relative rotation, one of the members having perforations therein and the other having a feedway in the surface thereof adjacent the 80 perforations.

2. A blending machine, comprising two closely fitting members mounted for relative rotation, one of the members having circumferentially spaced perforations therein 85 and the other having circumferentially spaced feedways in the surface thereof adjacent the perforations.

3. A blending machine, comprising a tubular stator having perforations therein, and 90 a closely fitting rotor in the stator having feedways in the outer surface thereof which revolve past the perforations in the stator.

4. A blending machine, comprising a tubular stator having perforations therein, and 95 a closely fitting rotor in the stator having longitudinally extending feedways in the outer surface thereof which revolve past the perforations in the stator.

5. A blending machine, comprising a tubular stator having perforations therein, and 100 a closely fitting rotor in the stator having longitudinally extending feedways in the outer surface thereof which revolve past the perforations in the stator and helically 105 extending feedways in the outer surface which intersect with the longitudinally extending feedways.

6. A blending machine, comprising a closed casing, a tubular stator having perforations therein, a closely fitting rotor in the stator having feedways in the outer surface thereof which revolve past the perforations in the stator, an outlet port in the 110 casing in communication with the perforations, and an inlet port in the casing in communication with the feedways. 115

7. A blending machine, comprising a hollow cylindrical stator having a band of fine perforations therein, and a partly cylindrical and partly conical rotor in the stator having longitudinally extending feedways in the cylindrical portion which revolve past the perforations in the stator and helically 120 extending feedways in the conical portion 125 which communicate with the longitudinally extending feedways.

8. A blending machine, comprising a closed casing, a hollow cylindrical stator in the casing having a band of fine perfora- 130

tions in the medial portion thereof; a medi-
ally cylindrical and laterally conical rotor
in the stator having longitudinally extend-
ing feedways in the outer surfaces of both
the cylindrical and conical portions and heli-
cally extending feedways in the outer sur-
face of only the conical portions, an outlet

port in the casing in communication with
the perforations, and an inlet port in the
casing in communication with the feedways. 10
In testimony whereof I have hereunto sub-
scribed my name.

BERTIE S. HARRINGTON.
